LAWN SPRINKLER

Robert O. Ernest, Oak Park, Ill., assignor to Sunbeam Corporation, Chicago, Ill., a corporation of Illinois

Filed May 19, 1959, Ser. No. 55,972

Term of patent 14 years

(Cl. D91—1)

Fig. 1 is a front perspective view of a lawn sprinkler embodying my design;

Fig. 2 is a front elevational view thereof;

Fig. 3 is a top plan view thereof; and

Figs. 4 and 5 are right side and rear elevational views, respectively, thereof.

The sprinkler head and coupling are omitted in Figs. 2, 3, 4 and 5 for convenience only. The dominant features of my design reside in the portions shown in full lines.

I claim:

The ornamental design for a lawn sprinkler, as shown and described.
